UNITED STATES PATENT OFFICE.

ALBERT LESLIE LAMBERT, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

GRAB-HANDLE FOR CAR-SEATS.

1,261,246.

Specification of Letters Patent.

Patented Apr. 2, 1918.

Application filed June 22, 1917. Serial No. 176,315.

To all whom it may concern:

Be it known that I, ALBERT LESLIE LAMBERT, a citizen of the United States, residing at Philadelphia, in the county of Philadelphia and State of Pennsylvania, have invented certain new and useful Improvements in Grab-Handles for Car-Seats, of which the following is a specification.

My invention relates to a pressed metal grab-handle adapted to be secured to a corner of the back of a railway car-seat. Grab-handles have previously been made of cast metal of either iron, steel or brass. My improved construction comprises a section of tubing which is notched at the ends of the curved handle portion, the end portions extending beyond the notches having the walls of the tube pressed together to form arched portions of double thickness adapted to lie against and be secured to the end and top edges of the seat-back. A cross-member is provided which is pressed with a die to an arched section with closed ends, the end portions of this cross-member being formed upwardly. This cross-member is positioned with its ends abutting the main member at the junctions of the end portions and the tubular central or handle portion. The two pieces are welded in this position and then ground down, the end portions of the cross-member joining the ends of the central portion of the main member to form a smooth curve. Projecting lugs are also preferably made of formed metal and welded to the cross-member, so as to extend into the edge of the seat-back at the corner to properly locate the handle.

The pressed metal handle as thus formed is much lighter than the cast metal handles as previously made, and further is considerably cheaper in manufacture than the cast metal handles. A further considerable advantage consists in the fact that a steel handle will take white enamel, particularly porcelain enamel very well, which is not the case with a malleable iron handle. Gray iron will take a white enamel, but must be large and bulky in order to get sufficient strength. Accordingly, my improved design affords a light, cheap and efficient construction which will take a desired finish, which is impossible with other handles which may be considered practicable.

In order that my invention may be more clearly understood, attention is hereby di-

rected to the accompanying drawings forming part of this application and illustrating certain embodiments of my invention. In the drawings Figure 1 represents a side elevation of my improved grab-handle applied to a car-seat back, Fig. 2 is an enlarged side elevation of the handle before welding the parts together, Fig. 3 is a similar view, showing the parts separated, and Figs. 4 and 5 are enlarged sections taken, respectively, on lines 4—4 and 5—5 of Fig. 2.

Referring to the drawings, the main piece 1 of the handle is made of a section of tubing, preferably of steel, which is notched, as indicated at 2, 2, and bent to the desired curvature. The end portions 3, 3 extending from the notches 2, 2 to the ends of the piece are straight and are given the conformation required to enable the same to lie against the end and top edges 4 and 5 of the seat-back 6. This is preferably accomplished by pressing the inner surface of the tubing against the outer portion of the tubing, so as to give the end portions of the piece an arched inwardly curved cross-section of double thickness, as indicated in Fig. 4. This, of course, insures rigidity in the portions of the handle which are to lie against and be secured to the seat-back. Suitable openings 7, 7 are formed through the end portions 3, through which screws 8 may be passed to secure the handle to the back 6.

The tubular central portion of member 1, indicated at 9, is preferably flattened somewhat in cross-section, so that its section is approximately oval. The extreme ends of the central portion, however, are not flattened, so that inwardly flaring end portions 10 are formed.

The cross-member 11 is also preferably made of steel and pressed in a die to the desired shape, this member being somewhat arched downwardly in cross-section. At its ends, the cross-member is pressed upwardly to form raised top portions 12 and closed end portions 13.

The lugs 14, which are adapted to be inserted in openings of the corner portion of the seat-back, are preferably pressed from sheet-metal and welded to the cross member 11, as shown. These lugs are preferably pressed into the form of cups, as shown in Fig. 5, with flanges 15 which are welded to the cross-member 11.

The cross-member is positioned across the central tubular portion of the main member with its closed end portions 13 resting in contact with the end portions 3 adjacent to the notches 2. When so positioned, the raised end surfaces 12 of the cross-member lie in contact with the lower edges of the flared ends 10 of the tubular portion 9. The members are now welded together in this position, after which the welded joint is ground down, so that the outer surfaces of the handle member and the cross-member join together smoothly and continuously, the end portions of the cross-member, and the flared ends 10 of the handle portion 9 joining to form a smooth curve, as indicated at 16, in Fig. 1. The completed handle may be mounted as indicated in Fig. 1.

What I claim is:—

- 20 1. A grab-handle of pressed metal comprising a curved member having a tubular central portion and end portions of inwardly arched cross-section, and a cross-member of downwardly arched cross-section with closed ends, welded at its ends to said curved member adjacent the ends of said tubular central portion, the end portions of said cross-member being formed upwardly to join the ends of said tubular portion, substantially as set forth.
- 30 2. A grab-handle of pressed metal comprising a curved member formed of tubing, having a tubular central portion and end portions of double thickness, the inner side of the tubing being pressed against the outer side, and a cross-member of downwardly arched cross-section with closed ends, welded at its ends to said curved member adjacent the ends of said central portion, the ends of said central portion and the end portions of said cross member being so formed as to join together, at their inner surfaces, with a smooth curve, substantially as set forth.
- 35 3. A grab-handle of pressed metal comprising a curved member having a tubular central portion and straight end portions adapted to be secured to an end and top edge of a seat-back, and a cross-member se-

cured at its ends to said curved member adjacent the ends of said central portion, said 50 cross-member having end surfaces contacting and secured to said straight end portions, said tubular central portion of the curved member having flared ends, and said cross-member having curved surfaces adjacent its ends which join said flared ends, when said cross-member is secured in position, with a smooth curve, substantially as set forth.

4. The process of forming a grab-handle 60 for car-seat backs, comprising, notching a length of metal tubing at a pair of intermediate points, bending the portion between the notches to a desired curvature, pressing down the end portions beyond the notches to 65 form sections adapted to lie against edges of the back, and securing a cross-member across the curved member so that its end portions will lie adjacent to and be continuous with the ends of said tubular curved 70 portion of said curved member, substantially as set forth.

5. The process of forming a grab-handle for car-seat backs, comprising, notching a length of metal tubing at a pair of intermediate points, bending the portion between the notches to a desired curvature, forming the end portions beyond the notches to form 75 sections adapted to lie against edges of the back, pressing a cross-member of sheet-metal 80 with channel section, pressed-up end portions and closed end surfaces, and welding the cross member across the curved member, so that its end surfaces will be welded to said end portions and its pressed-up end 85 portions will be welded to, and continuous with, the ends of the tubular curved portion of the curved member, substantially as set forth.

This specification signed and witnessed 90 this 11 day of May, 1917.

ALBERT LESLIE LAMBERT.
